UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

STEAM-BOILER.

1,250,181.

Specification of Letters Patent. Patented Dec. 18, 1917.

Application filed April 10, 1916. Serial No. 90,060.

To all whom it may concern:

Be it known that I, DAVID S. JACOBUS, a citizen of the United States, residing at Jersey City, in the county of Hudson and 5 State of New Jersey, have invented certain new and useful Improvements in Steam-Boilers, of which the following is a specification.

My invention relates to steam boilers, and 10 more particularly to a new superheater arrangement, and will be understood by reference to the accompanying drawings in which Figure 1 is a longitudinal section through a boiler showing the superheater near the 15 front of the front bank of tubes, the view being more or less diagrammatic, and the furnace omitted; Fig. 2 a detail of the means for supporting a tile baffle between a portion of the superheater and the fur- 20 nace; Fig. 3 a sectional view and Fig. 4 a side view, illustrating a form of baffle which may be used in place of that of Fig. 2; Fig. 5 a longitudinal section through a boiler showing a modification in which two 25 superheaters are employed; and Fig. 6 a detail of the means for supporting the tile at the rear of the line of tubes which comes nearest the furnace. Similar reference numerals indicate similar parts in the several 30 views.

Referring to Fig. 1, the boiler shown is of the general Stirling type comprising transverse steam and water drums 1, 2 and 3, and a lower mud drum 4, the upper and 35 lower drums being connected by three banks of tubes 5, 6 and 7. The middle steam and water drum is connected with the front drum 1 by steam and water circulators, and to the rear steam and water drum by steam 40 circulators, as shown. A baffle 8 is supported upon one of the rows of tubes of the first bank, near the front thereof, and extends upward from a point at the rear of the bridge wall 9, so that the gases will be 45 directed, substantially as indicated by the arrows, across the top of the front bank into the secondary combustion chamber at the rear of said bank. A baffle 10 is shown as supported upon the front row of tubes

of the middle bank and extending downward from the middle steam and water drum. A baffle 11 is supported upon the rear row of tubes of the middle bank and extends upward from the mud drum 4. In the particular system of baffling shown, 55 the third or rear bank of tubes is provided with a baffle 12 extending downward from the rear steam and water drum. The gases, after crossing the top portion of the front bank of tubes flow into the secondary com- 60 bustion chamber, at the rear of said bank, and thence in a downward direction over the tubes of the front bank at the rear of the baffle 8 and the front row of the second bank, thence upward along the tubes of the middle bank, downward over the tubes of the rear bank to the outlet 13. A cross- 65 baffle or shelf 11' extends from the baffle 11 so as to direct the gases into the tubes of the rear bank. 70

At the rear of the bridge wall is a cross- 75 box 14 which is connected with the front steam and water drum by additional water tubes 15, the alternate tubes being bent at a point above the bridge wall, substantially as shown in Fig. 1, to thereby stagger the tubes above the bends to permit of the placing of a baffle 16 between them so as to direct a portion of the furnace gases to the upper ends of said tubes. The cross-box 80 14 is connected by nipples 17 with the mud drum and they are spaced far enough apart to allow a man to pass between them. The tubes 15 are so located relatively to the front bank 5 as to permit of the placing 85 of a superheater in the space between said tubes and bank. This superheater comprises the cross-boxes 18 and 19 extending between the side walls and connected by inverted U- 90 tubes 20. The boxes are located in the lower part of the space between the tubes 15 and the bank 5, and the superheater tubes extend approximately to the upper end of the baffle 16. Placed over the boxes 18 and 19 are tiles 21 to prevent short circuiting 95 of the gases around the boxes to the lower end of the front bank of tubes. The steam from the middle drum 2 flows through pipe

22 to box 18 and is delivered to the steam main from box 19. The superheater is so set that short cores may be used in the tubes or, if desired, jointed cores may be 5 employed to extend the full length of the straight portion of the tubes. The furnace gases are directed substantially as indicated by the arrows, those passing between the lower ends of the tubes 15, below baffle 16, 10 passing upward over the superheater and mingling with those which cross the upper ends of the tubes 15 and the front bank of tubes. By altering the height of the baffle 16, different degrees of superheat may be 15 secured. A seal 23 is shown between the cross-box 14 and the bridge wall to prevent the furnace gases short circuiting beneath the cross-box. The bridge wall 9 should be built high enough to prevent the radiant 20 heat from the furnace fluxing or caking the dust which collects above this seal. A dusting door 24 is provided in the side of the setting opposite the seal 23 for removing any dust which may collect above said seal. 25 Instead of the flat tiling used for the baffle 16, as shown in Figs. 1 and 2, I may employ tiles 25 substantially semi-circular in cross-section, as shown in Figs. 3 and 4. This form of tiling may be installed by rotating them around the tubes into the positions indicated in the drawings.

In Fig. 5 I have shown a boiler having a single row of tubes 26 in front of the front bank of tubes and not staggered rows as in 35 Fig. 1. To support the baffle 16 upon the single row of tubes 26, small steel or iron lugs 27 are secured to the tubes by any suitable means, preferably by welding, as indicated in Fig. 6. The lower tiles constituting the baffle 40 are notched so as to cover the supporting lugs and to protect them from the direct heat of the gases. The baffling for the banks of tubes is substantially the same as in Fig. 1, but the rear wall of the setting is so placed 45 as to provide a gas passage back of the rear bank of tubes to permit the gases to escape at the outlet which is here located at the top of the setting, instead of at the lower part thereof as in Fig. 1. 50 In the design of Fig. 5 I have also introduced a superheater into the secondary combustion chamber at the rear of the front bank of tubes, said superheater comprising boxes 28 and 29 connected by inverted U- 55 tubes 30. The steam from the boiler flows through the pipe 22 to box 28 and is conducted from the outlet box 29, by a pipe 31, to box 18 of the superheater in front of the front bank of tubes. In this design the 60 steam to be superheated is first subjected to the heat of the gases flowing over the upper part of the front bank of tubes and then to those which enter below the baffle 16 and

flow upward along the tubes of the superheater in front of the front bank of tubes. 65

The secondary combustion space between the additional water tubes connecting the mud drum and the first steam and water drum, and the first bank of tubes leads to a substantially complete combustion of the 70 combustible elements in the gases, and even in cases where the superheater is omitted an active secondary combustion is promoted, which, in addition to increasing the efficiency, will minimize smoke. The secondary 75 combustion around the superheater, when one is used, increases the superheat.

What I claim and desire to secure by Letters Patent of the United States is:

1. A water tube boiler having a plurality 80 of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space between said additional water tubes and the first bank of tubes, and baffling arranged to give an upflow of gases over the superheater. 85 90

2. A water tube boiler having a plurality of transverse steam and water drums, a mud drum, banks of tubes connecting the steam and water drums with the mud drum, additional water tubes connecting the mud drum with the first steam and water drum and in front of the first bank of tubes and separated therefrom, and a superheater in the space between said additional water tubes and the first bank of tubes, said superheater comprising cross boxes in the lower part of 95 said space and connected by tubes extending upward therefrom, and baffling arranged to give an upflow of gases over the superheater. 100

3. A water tube boiler having a plurality 105 of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space between said additional water tubes and the first bank of tubes, and a baffle supported by 110 said additional tubes and arranged to permit furnace gases to enter the lower part of said space to flow upward over the superheater tubes. 115

4. A water tube boiler having a plurality 120 of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space 125

- between said additional water tubes and the first bank of tubes, and a baffle supported by said additional tubes arranged to direct a part of the furnace gases below said baffle 5 and a part above said baffle.
5. A water tube boiler having a plurality of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space between said additional water tubes and the 10 first bank of tubes, baffling arranged to give an upflow of gases over the superheater, and means to prevent short-circuiting of the gases around the lower ends of said additional tubes.
- 20 6. A water tube boiler having a plurality of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space between said additional water tubes and the first bank of tubes, and baffles to 25 direct gases upward over the superheater tubes and thence downward over the first bank of tubes.
7. A water tube boiler having a plurality of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space 30 between said additional water tubes and the first bank of tubes, a baffle supported by said additional tubes and so placed as to permit the gases to enter the lower part of said 35 space and a baffle at the front of the first bank of tubes arranged to allow part of the rising gases to pass over into the top of the front bank.
- 45 8. A water tube boiler having a plurality of transverse steam and water drums, a mud drum, banks of tubes connecting the steam and water drums with the mud drum, a transverse water box connected to the mud drum, water tubes connecting said box with the first steam and water drum, a superheater in the space between said water tubes and the first bank of tubes, and baffling arranged on said water tubes to give an upflow 50 of gases over the superheater.
- 55 9. A water tube boiler having transverse steam and water drums connected by banks of tubes to a transverse mud drum, a furnace bridge wall, a cross-box at the rear of
- said wall, water tubes connecting said cross-box with the first steam and water drum and 65 nipples connecting said cross-box with the mud drum, said nipples being spaced far enough apart to allow a man to pass between them.
10. A water tube boiler having transverse steam and water drums connected by banks of tubes to a transverse mud drum, a furnace bridge wall, a cross-box at the rear of said wall, water tubes connecting said cross-box with the first steam and water drum, 70 nipples connecting said cross-box with the mud drum, said nipples being spaced far enough apart to allow a man to pass between them, and a seal between said bridge wall and cross-box to prevent short circuiting of 75 the gases below the lower ends of said tubes.
11. A water tube boiler having a plurality of transverse steam and water drums and mud drums, banks of tubes connecting the steam and water drums with the mud drum, additional water tubes connecting the mud drum and the first steam and water drum and in front of the first bank of tubes and separated therefrom, a superheater in the space between said additional water tubes and the first bank of tubes, a superheater at the rear of the first bank of tubes, and a steam connection between said superheaters. 80
12. A water tube boiler having a plurality of transverse steam and water drums, a mud drum, banks of tubes connecting the steam and water drums with the mud drum, additional water tubes connecting the mud drum with the first steam and water drum and in front of the first bank of tubes and separated therefrom, a superheater in the space between said additional water tubes and the first bank of tubes, an inverted U-tube superheater at the rear of the first bank of tubes, and a steam connection between the outlet of 85 said last-named superheater and the inlet of the first-named superheater.
13. A water tube boiler having a plurality of transverse steam and water drums, a mud drum, banks of tubes connecting the steam and water drums with the mud drum, the first bank having rows of tubes in front of a plane passed through the axes of the mud drum and the first steam and water drum, additional water tubes connecting the mud drum with the first steam and water drum and in front of the first bank of tubes and separated therefrom, and a baffle supported upon said additional tubes to direct a portion of the rising gases into the lower part 100 of the space between the additional tubes and the first bank.
14. A water tube boiler having a plurality of transverse steam and water drums, a mud drum, banks of tubes connecting the steam and water drums with the mud drum, addi- 105

- 115
- 120
- 125

4
tional water tubes connecting the mud drum with the first steam and water drum and in front of the first bank of tubes and separated therefrom, and a baffle forming the 5 rear of the combustion chamber and so placed as to direct a portion of the furnace gases upward to the top of the first bank of tubes and permit another portion of the gases to enter the lower part of the space be-

tween said additional tubes and the first 10 bank of tubes.

In testimony whereof I have hereunto signed my name in the presence of two subscribing witnesses.

DAVID S. JACOBUS.
